US00D576725S

(12) **United States Design Patent**
Shumer et al.

(10) **Patent No.:** US D576,725 S
(45) **Date of Patent:** ** Sep. 9, 2008

(54) **MEDICAL DEVICE DELIVERY HANDLE**

(75) Inventors: **Dan Shumer**, San Jose, CA (US); **Nie Tang**, San Jose, CA (US); **Sanjay Shrivastava**, Mountain View, CA (US); **Pete Lombrozo**, Scotts Valley, CA (US); **Josh Druker**, San Francisco, CA (US)

(73) Assignee: **Abbot Laboratories, Inc.**, Abbott Park, IL (US)

(**) Term: **14 Years**

(21) Appl. No.: **29/281,312**

(22) Filed: **Jun. 20, 2007**

(51) **LOC (8) Cl.** 24-02

(52) **U.S. Cl.** D24/133

(58) **Field of Classification Search** D24/133, D24/145, 112, 130, 147; 600/131, 156; 604/118, 604/119; 606/108

See application file for complete search history.

(57) **CLAIM**

The ornamental design for a medical device delivery handle, as shown and described.

DESCRIPTION

FIG. 1 is a perspective view of a medical device delivery handle showing our new design;

FIG. 2 is a side view thereof;

FIG. 3 is another side view thereof;

FIG. 4 is a top plan view thereof;

FIG. 5 is a bottom plan view thereof;

FIG. 6 is a front elevational view thereof; and,

FIG. 7 is a rear elevational view thereof.

The portions of the article in broken lines are shown for illustrative purposes only and form no part of the claimed design.

1 Claim, 5 Drawing Sheets
